UNITED STATES PATENT OFFICE

JOHN O. CARREY, OF ST. LOUIS, MISSOURI, ASSIGNOR TO C. & C. ENGINEERING COMPANY, INC., OF ST. LOUIS, MISSOURI, A CORPORATION OF MISSOURI

VACUOUS REFRIGERATOR AND METHOD OF MAINTAINING VACUUM THEREIN

Application filed February 25, 1926. Serial No. 90,550.

This invention relates to new and useful improvements in refrigerators and a novel method of heat-insulating the walls of refrigerators, enameling ovens, furnaces, and 5 the like.

Further objects of the invention are to provide a refrigerator or other heat-insulating structure having double walls insulated from each other and hermetically sealed whereby 10 the spaces between said walls can be placed in vacuum or partial vacuum to prevent radiation of heat through said walls.

Still further objects of the invention are to provide suitable reinforcing means insertable 15 between the spaced walls to strengthen the latter, said means being provided with suitable passageways to permit intercommunication therethrough.

With these and other objects in view, my 20 invention consists in certain novel features of construction and arrangement of parts, hereinafter more fully described and claimed, and illustrated in the accompanying drawings, in which—

25 Figure 1 is a perspective view of a refrigerator of my improved construction.

Figure 2 is a front elevational view, partly 30 in cross section, with the doors thereof removed.

Figure 3 is a vertical cross section taken on line 3—3 of Figure 2.

Figure 4 is a detail view of the door latch.

Figure 5 is a detail cross section showing the construction of the joint of the spaced 35 wall members.

Figure 6 is a perspective view of the refrigerator with the casing thereof partly broken away and the doors removed.

Figure 7 is a horizontal cross section taken 40 on line 7—7 of Figure 6.

Figure 8 is a fragmental front elevational view of the reinforcing means used in the construction of the refrigerator casing.

Figure 9 is a detail sectional view of said 45 reinforcing means.

Figure 10 is a detail view showing the construction of the vent opening for the refrigerator casing.

Referring by numerals to the accompanying 50 drawings, 10 indicates a refrigerator

casing comprising top and bottom walls 11 and 12, respectively, side walls 13, rear wall 14, and doors 15. The doors are hinged at 16 to the side walls 13 and are locked in closed position by latches 17 which are secured to 55 said doors and engage a notched bar 18 which projects from central rail 19. The walls of the refrigerator are made of an inner sheet member 20 and an outer sheet member 21, preferably formed of metal and said members 60 are spaced from each other to provide a chamber 22 which is co-extensive with said walls. These sheet members are preferably formed to provide two box-shaped members, the inner one of which is nested within the 65 outer one and spaced therefrom a suitable distance to form chamber 22. The marginal flanges of said sheet members of box-shaped structures are joined together and form tight 70 door openings for the refrigerator casing. This joint is illustrated in Figure 5 and is so constructed that while it forms an air-tight joint, said members 20 and 21 do not form any direct contact with each other but are 75 insulated to prevent radiation of heat therebetween.

In forming this joint, the edge 20^a of member 20 is bent obliquely to member 20 and the edge 21^a of member 21 is bent outwardly 80 parallel with portion 20^a and is then rebent inwardly to form a pocket 23, in which the bent edge 20^a is received. A U-shaped strip 24 of heat non-conducting material such as asbestos is placed over the bent edge 20^a and a thin sheet 25 of lead is then placed over the 85 U-shaped strip 24 and the whole is then forced into the pocket 23, and the assembled joint has the lead covering 25 bearing against the inner face of rebent edge 21^a and the edge 20^a is insulated from said lead covering and 90 from edge 21^a by asbestos covering 24.

If desired, the rebent portion 21^a may be now crimped at opposite points a—a to form 95 an air-tight joint and secure the edges of members 20 and 21 in assembled relation. The edges of the spaced wall members of doors 15 may be joined in a similar manner.

To prevent buckling or collapsing of the sheet walls of the refrigerator when the air is exhausted from chamber 22 and the cham- 100

bers of walls 15, I insert reinforcing members 26, preferably consisting of lattice work formed of wood or other material which is a poor conductor of heat. This lattice work 26 consists of members 27 spaced a suitable distance from each other and assembled in any suitable manner. The edges of these members are rounded or tapered as indicated at 27^a so as to minimize the surface contact of said members with the inner faces of members 20 and 21 and provide interconnecting passageways 28 through which air may circulate during the exhausting operation.

The air is exhausted from chamber 22 by a vacuum pump (not shown) which is connected by a pipe connection 30 to a trap or mercury reservoir 31, the latter being arranged to one side of casing 10. A pipe 32 extends vertically from reservoir 31 and has its upper end connected to chamber 22 as indicated at 33 in Figure 3. Reservoir 31 contains a certain amount of mercury and the lower end of tube 32 terminates a short distance above the bottom of reservoir 31, while the pipe 30 is connected to the upper portion of reservoir 31 as indicated at 34, and a suitable distance above the level of mercury contained in said reservoir. Pipe 32 is of sufficient length so that when the air is exhausted from chamber 22 and the mercury rises in said tube due to atmospheric pressure, the top of the mercury will be a suitable distance below connection 33 to prevent admission of mercury into the chamber. As the mercury will rise in the tube 32 to a height of about seventy-six centimeters, connection 33 would have to be a short distance above that.

While the exhausting apparatus and connections form a permanent part of the refrigerator, casing doors 15 may be exhausted by being placed in position and permanently sealed so that no exhausting operations will be necessary for the doors.

The drawers (not shown) are supported within the casing by means of framework 36 which is removably arranged in the interior of the casing. This framework consists of rectangular pieces or frames 37 connected together by top and bottom transverse members 38. Frames 37 are provided with vertically disposed intermediate members 39 which support a partition wall 40 and divides the interior of the refrigerator into two compartments A and B.

55 A series of tracks or ledges 41 are arranged in each compartment at suitable heights and form supports for said drawers.

A pipe connection 49 extends through chamber 22 between members 20 and 21 and is insulated therefrom and forms a vent connection for the interior of the casing.

I claim:

1. The method of constructing refrigerators consisting in forming the walls thereof of spaced outer and inner shells, bracing said

shells throughout their entire areas against atmospheric pressure by suitable heat non-conducting spacers arranged so as to allow unobstructed passage through said chambers exhausting the air from said chambers and maintaining said chambers under partial vacuum.

2. In a heat insulating container, the combination of an outer metallic shell, an inner metallic shell wholly spaced from the first shell to form a single peripheral chamber, one side of said container being provided with a door opening; said opening consisting of the edges of the inner shell, a heat insulating member bent U-shape over said edges, means for securing said insulating member in position, and the edges of said outer shell crimped over said means in insulated relation with the edges of said inner shell to provide a hermetically sealed joint for said peripheral chamber; and a closure member for said opening.

3. In a heat insulating container, the combination of an outer metallic shell, an inner metallic shell wholly spaced from the first shell to form a single peripheral chamber, one side of said container being provided with a door opening; said opening consisting of the edges of the inner shell, a heat insulating member bent U-shape over said edges, means for securing said insulating member in position, and the edges of said outer shell crimped over said means in insulated relation with the edges of said inner shell to provide a hermetically sealed joint for said peripheral chamber; a closure member for said opening, and a material supporting framework disposed within said inner shell.

4. In a heat insulating container, the combination of an outer metallic shell, an inner metallic shell wholly spaced from the first shell to form a single peripheral chamber, one side of said container being provided with an outwardly flared door opening; said opening consisting of the edges of the inner shell bent obliquely, a heat insulating member bent U-shape over said edges, means for securing said insulating member in position, and the edges of said outer shell bent into U-shape to fit over said means and said U-shaped insulating member and insulated from the edges of said inner shell to form obliquely disposed walls for said door opening; and a door for said opening and insulated from said inner shell.

5. In a heat insulating container, the combination of an outer metallic shell, an inner metallic shell wholly spaced from the first shell to form a single peripheral chamber, one side of said container being provided with an outwardly flared door opening; said opening consisting of the edges of the inner shell bent obliquely, a heat insulating member bent U-shape over said edges, means for securing said insulating member in position, and the edges of said outer shell bent into U-shape to fit over said means and said U-shaped insulating

member and insulated from the edges of said inner shell to form obliquely disposed walls for said door opening; a door for said opening and insulated from said inner shell, and
5 a material supporting framework removably arranged within said inner shell.

In testimony whereof I hereunto affix my signature this 19th day of January, 1926.
JOHN O. CARREY.
